UNITED STATES PATENT OFFICE.

CHARLES W. EATON, OF CHICAGO, ILLINOIS.

CONCRETE-SUPPLYING APPARATUS.

1,040,656.

Specification of Letters Patent.

Patented Oct. 8, 1912.

Application filed December 19, 1910. Serial No. 598,237.

To all whom it may concern:

Be it known that I, CHARLES W. EATON, citizen of the United States, residing at Chicago, in the county of Cook and State 5 of Illinois, have invented certain new and useful Improvements in Concrete-Supplying Apparatus, of which the following is a specification, reference being had therein to the accompanying drawing.

10 The general object of this invention is to provide apparatus for supplying concrete at various points where it may be needed in forming concrete structures, at such rate as best suits the particular work, and at 15 unusually low cost for handling the material.

In the accompanying drawings, Figure 1 is a side elevation of the apparatus, a portion 20 of a concrete wall under construction being shown in cross-section. Fig. 2 shows the same apparatus, looking from the left in Fig. 1. Fig. 3 is a sectional plan view, section being made on the line 3—3 Fig. 4 and the upper part of the apparatus being 25 removed. Fig. 4 is a section on the line 4—4, Fig. 3. Fig. 5 is an enlarged sectional elevation of a tank seen also in Figs. 1 and 2. Fig. 6 is an enlarged plan view of spout shown in Fig. 1. Fig. 7 is a section on the 30 line 7—7, Fig. 6. Fig. 8 is a section on the line 8—8, Fig. 7. Fig. 9 is a perspective view of one of the spout elements.

In these figures, A represents any suitable track alongside the foundation B of a wall 35 B' and C a concrete mixer, without novelty, supported by a wheeled carriage D resting on said track. Dry constituents of concrete are supplied to the mixer by an elevator E, without novelty, water is delivered 40 in the mixer from a tank F, and the mixed material is delivered to the work by a spout G.

Usually the track follows approximately the direction of the foundation so that the 45 carriage may be pushed along the track without moving so far from the foundation as to interfere with delivering material directly upon the same. Where vertical walls are to be formed, the carriage is usually of 50 skeleton - metal - tower form, sections D², D³ &c., being added to a lower section D' as the work progresses. To the upper part 55 of the carriage is secured, by bolts, an annular horizontal gear H and above this gear is a platform H' supporting the mixer and itself supported by rollers or wheels H'',

running upon the upper face of the gear, and held against lateral displacement by rollers H³ resting against the inner edge of the annular gear. To the lower face of the 60 platform H' is fixed an electric motor I the shaft I' of which drives a sprocket chain I² which extends upward through the platform and rotates the mixer by means of devices having no novelty. At the discharge 65 end of the mixer is the spout G pivoted at G' in plate-like brackets G² which are fixed to the platform. The spout is adapted to swing vertically, while the elevation of the other end is maintained by any suitable devices, shown as a pin G⁴ inserted below the spout in one of several holes G⁵ in the brackets. Upon the platform is also fixed a rigid frame J which overhangs the mixer and bears a charge hopper J' arranged to discharge 70 into the mixer through a passage controlled by a common form of valve J² operated by a hand lever J³. Dry concrete materials are delivered in the hopper J' by the elevator E which in itself has no novelty 75 and which is supported from the carriage by means of brackets E', E² and driven by a sprocket chain E³ from a second electric motor E⁴ preferably supported by the carriage and upon the bracket E'. 85

At the lower end of the conveyer is centrally hinged a hopper or platform E⁵ the bottom of which should be horizontal and near the ground, as shown in dotted lines, when it is to be loaded. When a proper 90 amount of one ingredient of the concrete has been shoveled or dumped from a wheelbarrow into this hopper, an attendant instantly raises it to the position shown in full lines, throwing its load into the conveyer casing. When the hopper is in this position no laborer can dump into it wrong material, and thus the attendant in charge of the hopper easily insures the proper proportions of different ingredients no matter 95 how rapid the operation may be, and the materials are thus supplied to the charging hopper in proper proportions. The tank F, also, is supported by the overhanging frame J and discharges into the mixer through a 100 pipe F' having a hand valve at F², preferably of the common instantaneously-acting lever-operated type. Water is supplied to the tank through a hose pipe F³, a pipe F⁴, provided with a common pressure regulating valve F⁵ and having its pendant discharge-end segment F⁶ in the axis of the 110

rotary platform and passing down through the charging hopper into the tank F. Preferably the maximum level of the water in the tank is controlled by common float-valve devices. The mixed concrete is dumped into the spout G by devices without novelty. This framework of the spout consists of two parallel bars K of such length as to reach the most distant point at which delivery is desired, and these are connected near each end by suitable cross-bars K'.

Above the cross-bars are trough-like spout segments K², K³, of metal, which are flanged upon the upper edges of the bars K and fixed thereto. The lower section K² has the upper portion of its flanges cut away, as shown at K⁴, and is overlapped by a like section K⁵ the flanges of which rest against preferably headed studs K⁶ fixed in the bars K, the flanges lying loosely beneath the heads of the studs, and the section K⁵ is in like manner overlapped by another like section, and so on. In each case the flanges of the sections K⁵ are cut back so that the section may slide upward on the side bars far enough to free it from the heads of the studs at its lower end, and hence any one of these sections may be quickly removed without disturbing any other part, and may be as quickly replaced. Thus if it be desired to discharge concrete at any point above the lower end of the spout, the corresponding section may be removed, leaving an opening, as at K⁷, Fig. 6, through which all the concrete falls. The same spout thus serves for delivery at all distances from the mixer. Obviously this is especially advantageous in forming horizontal concrete work, the sections being removed and replaced in succession; and by also moving the carriage step by step along its track, concrete may be readily discharged in desired quantities at all points of an extended horizontal plane, whereby little spreading or handling of the discharged material is required and a great saving in time and labor is effected.

The material may be delivered on any side or all sides of the carriage by rotating the platform with the mixer, spout, tank, motor, and charging hopper, about a vertical axis. This rotation is secured by means of a pinion M mounted on the platform in engagement with the fixed annular gear and itself rotated by any suitable means, for example, by a hand wheel M' fixed to its shaft. This expedient often saves many movements of the carriage whatever the class of work, and in building towers, or other structures having various portions approximately equidistant from a point where the carriage may be placed, the saving in time and expense is of still greater importance.

Where work is done near a water supply system, the water needed is elevated entirely without cost so long as the height of the

mixer is not above the level to which the water main pressure will carry the water, and in other cases the cost of raising the dry materials and the water separately is less than the cost of raising the mixed material, while accumulation of self-hardening concrete at any point in the elevating devices is entirely avoided.

What I claim is:

1. The combination with a suitable track, of a tower-like carriage arranged for movement along said track, a frame mounted upon the carriage to rotate about a vertical axis, a concrete mixer mounted upon said frame to rotate about its own horizontal axis, a mixer-actuating motor supported by and rotating with said frame, and means for at will rotating said frame through any desired angle with respect to the carriage.

2. The combination with a non-rotating, tower-like support, of a frame mounted upon said support for rotary adjustment about a vertical axis; a concrete mixer arranged for rotation about its own horizontal axis, a hopper for supplying solid materials to the mixer, a tank for supplying water to the mixer, and a motor for actuating the mixer, said mixer, hopper, tank and motor all being mounted upon said frame; means carried by the support for delivering solid materials and water in said hopper and tank, respectively; and means for at will rotating the frame about said vertical axis.

3. The combination with a tower-like support, of a frame mounted upon said support for rotation about a vertical axis, a concrete mixer mounted on said frame, a motor carried by said frame and arranged to rotate the mixer upon its horizontal axis, a hopper carried by said frame, in the line of said axis, above the mixer and discharging into the same, a tank carried by said frame in the line of said axis, above the mixer and discharging into the same, and means carried by said support and free from said frame, for supplying materials, in the line of said axis, to said hopper and tank.

4. The combination with a suitable carriage, of a horizontal gear fixed to the top of the carriage, a horizontal platform revolvably mounted above the gear, a pinion revolvably mounted upon the platform and engaging said gear, and means for at will rotating the pinion and thereby compelling the platform to rotate, a concrete mixer fixed to the platform, and means for operating the mixer.

5. The combination with a rotary supporting structure rotatable about a vertical axis and a concrete mixer fixed thereto, of a charging hopper rotating with said structure and discharging into the mixer, means for supplying dry concrete material to said hopper, a water tank rotating with said structure discharging into said mixer, means

for supplying water to said tank, and means for controlling both discharges.

6. The combination with a suitable supporting structure, of a second structure rev-
5 elubly mounted upon the first, a concrete mixer, a charging hopper for the mixer, a water supply tank for the mixer and a motor for the mixer, all carried by said second structure, and means for supplying
0 dry material to said hopper and water to said tank.

7. The combination with a track and a wheeled carriage movable thereon, of a con-

crete mixer, a charging hopper, a water tank, an elevator for supplying the hopper, 15 a motor for the mixer, and a motor for the elevator, all carried upon said carriage, and means for rotating together said mixer, hopper, tank, and motor for the mixer, inde-
pendently of the carriage.

20

In testimony whereof I affix my signature in presence of two witnesses.

CHARLES W. EATON.
